UNITED STATES PATENT OFFICE.

ALFRED L. KRONQUEST, OF CHICAGO, ILLINOIS, ASSIGNOR TO CONTINENTAL CAN COMPANY, OF SYRACUSE, NEW YORK, A CORPORATION OF NEW YORK.

CAN-BODY MAKER.

Application filed August 9, 1921. Serial No. 490,895.

To all whom it may concern:

Be it known that I, ALFRED L. KRONQUEST, a citizen of the United States, residing at Chicago, in the county of Cook, State of Illinois, have invented certain new and useful Improvements in Can-Body Makers, of which the following is a description, reference being had to the accompanying drawings and to the figures of reference marked thereon.

The invention relates to new and useful improvements in machines for making can bodies, and more particularly to a machine for making the interlocked side seam for the can body.

An object of the invention is to provide a machine of the above type wherein the can body is moved continuously and at substantially uniform speed while interlocking the bent edges and while bumping down the interlocked edges to form the side seam.

A further object of the invention is to provide a machine of the above type wherein the horn around which the can bodies are formed and along which the can bodies are moved, moves with the can bodies during the bending of the metal to form the side seam and during the bumping operation.

A further object of the invention is to provide a machine of the above type wherein the edger for bending the side edges of the can body moves with the can body while in engagement with the metal and at substantially the same speed as the speed of movement of the can body.

A further object of the invention is to provide a locator for placing the folded edges, one within the other, and while the can body is moving along the supporting horn therefor.

A still further object of the invention is to provide a rectifier for engaging the ends of the can body adjacent the seam for evening the ends preparatory to bumping, which rectifier moves with the can body.

A still further object of the invention is to provide a machine of the above type with traveling trucks for moving the can body along the horn supporting the same, and wherein the rectifying finger is moved so as to withdraw the end of the can from engagement with the truck prior to the bumping operation.

A still further object of the invention is to provide a machine of the above type wherein the bumper moves with the can body and at substantially the same speed as the speed of the can body while said bumper is in engagement with the metal for bumping down the side seam.

These and other objects will in part be obvious and will in part be hereinafter more fully disclosed.

In the drawings which show by way of illustration one embodiment of the invention:

- Fig. 54 is a view in vertical section showing more or less diagrammatically the forming rolls and the horn at the forming station;
- Fig. 55 is a similar view showing the parts at the edging station; 105
- Fig. 56 is a similar view showing the parts in the region of the locator; 105
- Fig. 57 is a similar view showing the parts at the bumping station; 110
- Fig. 58 is a view similar to Fig. 57 with the bumper omitted and the seam finished;
- Fig. 59 is a view showing more or less diagrammatically the side edges of a can body before they are operated upon by the edger; 110
- Fig. 60 is a similar view after the edges have been folded or bent by the edger; 115
- Fig. 61 is a similar view after the bent edges have been hooked together by the locator; 115
- Fig. 62 is a similar view but showing the edges as positioned when they reach the bumper; 120
- Fig. 63 is a similar view but showing the edges bumped down and the same completed, and
- Fig. 64 is a plan view of a can body having a side seam formed on the machine. 125
- The invention is directed broadly to a machine for forming can bodies, and more

- particularly a cylindrical can body wherein the side edges forming the side seam are folded or bent, interlocked and bumped down, after which the side seam is soldered. 65
- 5 The present machine forms the can body from a blank, folds or bends the side edges, interlocks the same and bumps them down and then delivers the can bodies to a conveyor which carries the same to a suitable 70
- 10 soldering machine. 75
- The machine consists of a supporting framework which carries a horn supported at one end thereof only, and around which the can bodies are formed and along which the 15 can bodies are moved while the edges are being interlocked and bumped together. The blank is formed into a cylindrical can body by forming rolls of the usual character. These forming rolls are so positioned relative to the horn that the cylindrical can 20 body is formed around the horn. Said horn is provided with a guide bar having recesses which receive the side edges of the cylindrical can body. The can body is moved along 25 the horn by traveling trucks. These traveling trucks also serve to support the free end of the horn. There is a truck for each can body, and these trucks move continuously and at a uniform speed, so that the can body 30 after it is rolled into cylindrical form, is picked up by the truck and slid endwise of the horn and does not again stop or is it retarded in speed until the side seam is completed, so far as bending or folding, interlocking and bumping down the seam is concerned. 35 The traveling can body is first presented to the edging station. At the edging station there is an edger which has four motions. It moves up and down into contact with the metal and back and forth endwise. The motions of the edger are so timed that the edger moves with the can body while in contact with the metal and during the bending or folding of the metal. 40
- 45 Associated with the edger is a female die bar carried by the horn. Also associated with the edger is a clamping bar which clamps one side of the can body and holds the projecting edge a definite distance above the ledge on the female die bar so that the edger will form an inturned hooked portion. 50 After the edger has bent the side edges of the can body to form hooks adapted to be interengaged one with the other, then it leaves the metal and returns for the next can body. 55 As the can body moves along, the hook-shaped side edges pass through the locator, which, together with suitable guide bars and a supporting plate, causes the hooked edges to be interlocked and drawn together. 60 It is understood that during this operation of the locator and the parts associated therewith, the can body is continuing to move at the same uniform speed. The can body is next presented to the rectifying finger which is carried by and moves with the bumper. Said rectifying finger engages the ends of the can body adjacent the side seam, and if perchance the edges are not even, this rectifying finger will move the edges to bring them up to even position preparatory to the bumping down of the seam which of course, will hold said edges in fixed relation to each other. This rectifying finger also performs another function. 65
- As it moves the can body forward, it moves it out of contact with the steel plates on the truck which has been conveying the can body so that the end edges are entirely free from the truck when the side seam is bumped down. This is a particular advantage in forming the lock and lapped seam, that is, the side seam wherein, at the ends, the metal is merely lapped, while throughout the rest of the seam, the edges are interfolded or interlocked. When the ends are entirely free of the truck, the bumping down of the seam does not disturb the overlapped sections at the end of the seam. After the rectifying finger has evened up the ends, then the bumper comes down on to the seam and this bumper also has four motions, an up and down and a back and forth motion. These motions are so timed that the bumper while in engagement with the can body moves with the can body. There is an anvil carried by the horn which cooperates with the bumper in the forming of the side seam. After the side seam has been bumped down, then the can bodies are taken up by the conveyor and conveyed to the soldering machine while the trucks return idle to the receiving end of the machine. 70

- The general arrangement of the mechanisms and devices will possibly be more clearly understood by reference to Fig. 1. The machine comprises a main supporting frame 1 carried by legs 2, 2. On this framework is supported the various devices. The can body is formed from a blank of sheet metal and this blank is rolled into cylindrical form by forming rolls which are located at the left hand end of the machine as viewed in this figure and are indicated generally by the reference letter F. After the can body has been rolled into cylindrical form it is supported by and moved along a horn which is indicated at H in the drawings. The can body is moved along the horn by a series of traveling trucks which are indicated at T in the drawings. The cylindrical body is formed around the horn and is moved endwise along the horn by these trucks. The can body is presented first to an edging mechanism indicated at E where the side edges of the can body are bent so as to be interlocked to form a seam. After the edges have been

bent for interlocking, the can body then passes underneath a locator indicated at L in the drawings, which operates to place the bent edges one within the other. The can body is next presented to a rectifying device indicated at R in the drawings. This rectifying device engages the ends of the can body adjacent the interlocked side edges and brings the two edges even and moves the can body slightly away from the end plate on the truck, which engages and feeds the can body along the horn. The interlocked and evened up edges are then presented to a bumper indicated at B in the drawings, and this bumper operates to press the metal parts together, completing the seam. The can body is then finished as far as the bending of the metal is concerned and as it leaves the body maker it is delivered to a soldering machine for soldering the seam.

Body forming mechanism.

The body forming mechanism per se forms no part of the present invention but only in combination with the other mechanisms which form and complete the side seam. Brief reference only therefore, will be made to the various elements of the body forming mechanism. The blank from which the body is formed is fed endwise along a bed plate 3 between two rotating forming rolls 4 and 5. The upper roll 4 is mounted on a support 6 which is pivoted at 7 to the frame of the machine and a spring 8 bearing on the support yieldingly holds the two rolls in contact, or in engagement with the blank which forms the can body. The lower roll 5 carries a gear 9 which meshes with the gear 10 carried by the upper roll 4. The gear 9 in turn meshes with a gear 11 and gear 11 meshes with a gear 12 on a shaft driven by a belt pulley 13. The upper roll 4 is mounted at its ends in bearings 4' and the bearing is removably held in a recess in support 6 by a screw 4'', which is threaded in part into the bearing and in part into the support (see Figures 4^a and 4^b). The roller 5 is mounted in a similar bearing 5' held in the frame of the machine by screws 5''.

In front of the forming rolls is a steel plate 14 which aids in the shaping of the can body so as to form the seam into a true cylinder. This steel 14 is carried by an adjustable support 15 which is mounted on the main support for the upper forming roll. In rear of the forming rolls is another forming steel 16 which is carried by a support 17 and this support 17 is in turn mounted on the main support for the upper forming roll. The steel 16 can be adjusted both vertically and in a direction at a slight angle to the horizontal. There is another forming steel 18 carried by a bracket attached to the main support for the upper

forming roll. The forming rolls together with these forming steels shape the blank into a cylindrical can body.

Supporting horn.

The forming rolls form the blank into a cylinder about the horn H as shown in Fig. 54 of the drawings. The horn in the region of the forming rolls is much smaller in cross sectional area than the can body so as to permit the ready formation of the cylindrical body. The horn in the region of the forming rolls is provided with a bar 19 which in turn is provided with edge guiding recesses 20 and 21. The can body is indicated at C. The edge c engages the guiding recess 20 while the edge c' engages the recess 21. The can body thus supported by the horn is moved endwise along the horn by the feeding trucks which will be herein-after more fully described.

This supporting horn H is carried by a cross head 22 located at the extremely left-hand end of the machine and at the left of the forming rolls as viewed in Fig. 1. The horn throughout the remainder of its length is unsupported, except that it rests freely on the feeding trucks. This permits the cylindrical can body encircling the horn to be moved along the horn and off from the end thereof.

The supporting horn has an endwise reciprocating movement and this is accomplished in the following manner. The cross-head 22 is fixed to two rods 23, 23 which slide in bearing sleeves 24, 24 carried by the bed frame of the machine. These rods 23, 23 extend from the left side of the forming rolls to the right-hand side thereof where they are connected by a second cross head 25. This crosshead 25 is in turn connected to a link 26 and the link 26 is connected to the support for the edging tool, which support moves back and forth in the direction lengthwise of the horn and through the link 26 imparts movement to the horn. Referring to Figures 33 and 36 it will be noted that the cross head 25 is provided with a projecting plate 27, which overlies the horn and serves as a shield or guide to prevent the edges of the can body snapping out of the recesses in the guide bar on the horn.

Truck operating mechanism.

The trucks T consist of a body portion 28, an upright portion 29 and lugs 30. Lugs 30, 30 are perforated and there is a rod or pin 31 extending transfixedly across the truck and through opposed pairs of lugs. These rods or pins 31 of adjacent trucks are connected by links 32, 32 and this forms an endless chain or conveyor of which the trucks are a part. On the ends of the pins or rods 31 are rollers 33, 33. The upright portion 29 of the truck is provided with a

central recess 34 and the horn is cut away at the side portions and beneath its center so as to extend down into said recess 34. The upright 29 at each side of the recess 34 and at the extreme upper end thereof is provided with hardened steel plates 35, 35. It is on these steel plates that the horn rests.

10 Mounted on the main framework of the machine is a bed plate 36 which extends from end to end of the machine. This bed plate is shown in plan view in Fig. 30 of the drawings. Said bed plate has its ends tapered as indicated at 37 and is also provided with recesses 38, 38, extending lengthwise thereof. As clearly shown in Figures 3 and 6, the bottom of the truck rests on this bed plate and slides along the same while the trucks are travelling from the left-hand end of the machine to the right-hand end 15 thereof as viewed in Fig. 1. The rollers 33, 33 do not engage the bed so that the horn resting on the trucks is supported rigidly and directly by the bed, and therefore the downward pressure of the edger and bumper are received by this solid bed support.

13 The endless conveyor including the trucks runs over pairs of sprocket wheels 39, 39, there being one pair to each end of the machine. These sprocket wheels are provided with spaced grooved recesses which the rollers engage. At the lower part of the frame there are angle bars 41 which extend from end to end of the machine and the rollers 35 run on these angle bars, as the trucks move from the right-hand end of the machine to the left-hand end thereof, as viewed in Fig. 1. The sprocket wheels 39 at the right-hand end of the machine are mounted on a shaft 42. This shaft 42 is provided with bevelled gear wheel 43 at one end thereof which meshes with a bevelled gear wheel 44 on a vertical shaft 45 and the shaft 45 in turn carries a bevel gear 46 which meshes with a bevel gear wheel 47 on the end of the main driving shaft 48, which extends lengthwise of the machine and is provided with a belt wheel 49. The belt wheel 49 is connected to the shaft 48 by means of a friction clutch 50 and the shaft 48 may be turned if desired by a hand wheel 50. When the main shaft rotates the shaft 42 and the connected train of gears will be rotated and this, through the sprocket wheels 39 imparts movement to the endless conveyor and thus drives the trucks. The sprocket wheels 39 at the left-hand end of the machine are loosely mounted on a shaft 51 (see Fig. 6^a). This shaft 51 is mounted in bearings which are free to slide in slots 52 in the main frame and the shaft is shifted by means of adjusting screws 53. This provides a means for taking up slack in the endless conveyor. From above will be noted from the trucks one after the 60 other passes across the body forming sta-

tion F picking up a can body and sliding the same along the horn.

Edger mechanism.

The purpose of the edger mechanism as 70 referred to above broadly is to fold the side edges of the can body so that they may be interlocked. Attention is directed to Figures 59 to 63, inclusive, wherein the can body C is shown in the various stages 75 through which it passes in the interlocking of the side edges. In Fig. 59 it will be noted that the edges c and c' are substantially unbent; although slightly curved. In Fig. 60 the edge c is shown as bent outwardly and back upon itself to form a hook c²; the edge c' as shown is bent inwardly to form a hook c³. The hooks c² and c³ in Fig. 61 are shown as interlocked and in Fig. 62 brought together preparatory to 80 the bumping down of the seam and in Fig. 62, said hooked edges are bumped down into seams and thus joined.

The edger operates to form these hooked ends which are to be later located in interlocked relation and then bumped down. The forming of the hook ends is accomplished by means of a bending tool 54 which co-operates with a female die member 55 (see Figures 41 and 55) mounted in the 95 horn; said die member in the horn is in the form of a bar and is provided with projecting pins 56 which engage suitable recesses in the horn so that this die bar 55 becomes a fixed and rigid part of the horn. Said die member has a recess 57 into which the portion 58 of the edging tool passes. The edging tool engages the edge c of the can body and bends the metal down into this recess 57 thus forming the hook c². 100 The recess 57 is slightly back from the ledge 59 which serves as an edge gage for the edge c and determines the length of the hook. The edge c' rests on the inclined face 59' of the die member 55 and projects over 110 the upper edge thereof. The shoulder 60 on the edging tool 54 engages the portion of the edge projecting over the ledge 59 and folds it down thus forming the hook c³. The edge c' is clamped against the inclined edge 59' by a clamping bar 61, which 115 will be later described.

120 It will be noted that the horn moves endwise. At the time when the edger tool is forming the hooks in the side edges of the can body both the edger tool and the horn are traveling with the can body and at the same speed as the truck. Thus it is that the edges of the can body are bent for interlocking without even retarding the forward movement of the can body.

125 The edger tool 54 has therefore what might be called four motions. It moves downwardly into engagement with the metal, forwardly with the metal, then up- 130

wardly out of engagement with the metal and returns to its initial position while out of engagement with the metal. This is accomplished in the following manner.

5 Mounted on the frame work of the machine is a bracket 62 (see Fig. 6). This bracket is formed with an inclined face portion along which is moved a slide or carriage 63; said carriage is mounted in suitable guideways which are parallel with the longitudinal axis of the horn and the carriage is held in place on its guideways by plates 64. The carriage is moved endwise by means of cranks, 65, 65. The crank 65 forms a part 10 of the shaft 66, 66 respectively, and each shaft carries a beveled gear wheel 67 meshing respectively with gear wheels 68, 68 on the main shaft 48 (see Fig. 19^a). These cranks 65, 65 are each mounted in bearings 20 69 which are rectangular and these bearings are adapted to slide in vertical planes in slots 70, 70. They are however, confined from horizontal movement in the carriage and therefore as the cranks rotate these 25 bearings move the carriage back and forth in a direction parallel with the length of the horn.

26 Mounted on the carriage is a support 71 to which the edger 54 is fixed. The support 71 is moved up and down in the carriage, said support is raised or moved upwardly by means of springs 72 which are seated at their bottom ends in the carriage and at their upper ends in the support 71.

30 Said support 71 is moved downwardly by means of cranks 73, each of which carries a roller 74. The support is provided with a cam surface 75 with which these rollers 74 contact. This cam surface is so shaped and 35 proportioned that as the cranks rotate they engage the support with rather an easy movement as distinguished from an abrupt striking movement and move the support downwardly against the tension of the 40 springs. The edger 54 is secured by means of a bolt 76 to a bracket 77 which in turn is secured by bolts 79 to the support 71. Inasmuch as the main supporting bracket is 45 inclined, the path of movement of the edger is in a plane slightly inclined to the vertical. This is comparatively for the purpose of forming the hooks in the cam body so that they may be more easily interlocked and 50 bumped down.

55 The clamping bar 61 is mounted on a pivot rod 80 carried by the bracket 77 and this clamping bar therefore partakes of all the movements of the edger. It does, however, have an additional movement in this 55 pivot rod. Springs 81 engage the outer end of the clamping bar and yieldingly force the clamping face or inner end downwardly so that when the clamping bar engages the metal on the horn it will yieldingly 60 clamp the metal against the horn and

is brought into clamping engagement with the metal prior to the edger engaging the metal of the can body to bend the same. The bolts 76 which clamp the edger with the bracket 77 pass through elongated holes 82 70 in the edger and this affords a means for adjusting the edger in a direction toward and from the horn. The bolts 79 pass through elongated slots in the bracket 77 and this permits the bracket 77 to be moved so as to 75 adjust the edger laterally. Through these two adjustments the edger may be set so as to properly cooperate with the female die bar carried by the horn.

Can body guiding devices.

80 Associated with the horn are can body guiding devices which engage the can body at certain points on the outer surface thereof for holding the edges well up in the recesses in the guide bar in the horn and properly positioned relative to the female die bar and the edger tool to form the hooks. These guiding devices include side guide rails 83 and 83', one on each side of the 85 horn and spaced back from the horn as clearly shown in Fig. 13. The guide rails extend from a point adjacent to the right hand side of the forming rolls to a point midway of the locator.

90 Below the horn is a guiding device 84^a which guiding device has a curved upper face conforming with the curvature of the can body. As clearly shown in Fig. 13, these side guide rails and the curved guiding support beneath the horn hold the edges *a* and *a'* of the can body well up in the guiding recesses in the bar in the horn.

95 The guide rail 83 is carried by supporting blocks 84, said rail being secured to the 100 blocks by screws 85, 85. Each block 84 is adjustably secured to a bracket 86 by a bolt 87. The brackets 86 are secured to the frame of the machine by bolts 88. These brackets 88 are in yoke form. There are 105 two of these brackets 88 and mounted on each bracket is an extension which overhangs the horn. These extensions 89 carry the guide rail 83' at the other side of the horn. The extensions are adjustably secured to the brackets 88 by bolts 90. Thus the guide rails may be adjusted toward and from the upper central part of the horn, and this adjustment does not interfere with the trucks and at the same time brings the 110 edges of the can body into the proper position relative to the guide bar and the female die bar of the edger.

115 The guiding device 84^a beneath the can body extends from a point adjacent to the 120 right hand side of the forming rolls to a point midway of the locator, or, substantially throughout the same extent as the side guide rails. Said guiding device 84^a is however, secured to a bar 91 which in turn is 125 130

secured to a block or member 92. This block is provided with a threaded recess adapted to receive a bolt 93. The bolt 93 is provided with a collar 94 and said bolt extends freely 5 through a bracket 95 which in turn is bolted by bolts 96 to the frame of the machine (see Fig. 25). On the bolt 93 is a lock nut 97. By loosening the lock nut and turning the bolt the bar 91 may be moved endwise. 10 Extending alongside of the bar 91 and the guiding device 84^a are supporting parallel bars 98. These supporting parallel bars 98 are secured to lugs 99 by a pin 100. The supporting bars are connected by cross 15 pieces 101. Guiding bar 84^a overlaps and rests on the side bar supports 98 (see Fig. 28). The upper edges of the side bar supports 98 are provided with inclined surfaces 102 and the underside of the guiding device 20 84^a is provided with inclined projections 103 which engage and rest upon the inclined surfaces 102. By turning the threaded bolt 93 the supporting bars 98 are moved endwise and due to the inclined faces on said 25 bars the guiding device 84^a is raised or lowered at this free end relative to the side bars 98. The side bars 98 and the guiding device 84^a are located in the recesses 34 in the trucks and these side bars and the guiding 30 device rest on and are supported by the trucks. The guiding device 84^a as clearly shown in Figures 3 and 3^a is formed on different levels with an incline connected with the levels; the lowest level is indicated at 35 104—the highest level at 105 and the incline at 106.

In the region of the edging device, the edges are properly held relative to the female die for the forming of the hooks and 40 as soon as the can body leaves the female die it is desirable to move the hooks forward and to the position shown in Fig. 13, where one hook is over the top of the other. As the can body passes up the incline 106 45 on the level 105, the edges will be positioned as noted above.

Locater mechanism.

At this time the edges are passing through 50 the locator L which is in the form of a guide bar (see Figures 13 to 15) carried by a bracket 107, said bar being bolted to the bracket by bolts 108^a. The bracket is in turn bolted to the side of the bracket 86 by bolts 109. The recesses in the bar 55 is now 55 slightly changed in shape as shown in Figures 13, 46, 47 and 56. The projecting ledge 108 is slightly extended and aids in carrying the hooks *c*³ upwardly to a point over the hook *c*². The forcing upwardly of the side edges on the can body by the guiding device 84^a as the body passes on the higher level 105 also forces the edges to overlapped 60 position. The locater bar L is provided with 65 a shoulder 109^a which inclines slightly as

shown in Figures 14 and 15. The hook *c*³ engages this shoulder and is guided thereby while the hook *c*² is moved underneath the hook *c*³.

After the hook ends are interlocked as 70 shown in Fig. 61, then the can body passes on to the enlarged section 110 of the horn and as this enlarged section approaches in cross-sectional area the cross sectional area of the can body much more nearly the hook 75 edges will be held drawn together and interlocked as shown in Fig. 62.

Rectifying mechanism.

As the can body approaches the bumping 80 station the rectifier R comes into play to even up the edges. Said rectifier consists of a pivoting finger 111. Said pivoted finger 111 is carried by the support for the bumping die. The finger is pivoted at 112 to the support and the spring 113 normally forces the rectifying finger to the left as viewed in Fig. 20. Said rectifying finger 111 at its lower end has a beveled portion 114. At the end of the bar 55 there is a hardened 90 steel plate 115 which has a rounded corner 116 (see Figures 44 and 52). This rounded corner on the plate 115 lies in the path of the beveled end 114 so that as the rectifying finger descends it moves down 95 into a groove in the horn and the beveled end thereof engages the face 116 and this forces the rectifying finger forwardly. The parts are so timed that this rectifying finger comes down just behind the can body and 100 the forward movement of the finger due to the cam or rounded portion 116 working on the beveled portion of the finger moves the finger a little faster than the travel of the truck and the travel of the horn and 105 causes the flat face of the finger to engage the ends of the can body at the side seam and if these ends are not properly even it will force the one on the other forward until they are even. (See Fig. 53, where the ends of the can body are indicated at *e* and *e'*.) This same movement of the rectifying finger moves the can body slightly away from the steel plates 35 on the trucks so that when the side seam is bumped it is 115 free from the truck as well as having its edges properly evened up.

Bumping mechanism.

The can body is positioned by the rectifying finger and the traveling truck is directly over the anvil 117. This anvil is formed with a central recess 118 for the side seam of the can body and with the flat portions 119 for the overlapped side edges which are 120 not interlocked. It will be understood from Fig. 64 of the drawing that the interlocked part of the seam does not extend the full length of the can body but at portions adjacent the ends of the seam the metal is 125 130

flat and overlapped and not interlocked. While one of the flat edges rests on the surface 119 the other rests on the surface 120 which is raised above the surface 119, the thickness of the metal. When the can body is brought over the anvil the bumping mechanism comes into play which consists of a bumping hammer 121 which not only moves up and down but travels with the horn and can body while it is bumping down the seam. Said bumper is carried by a supporting carriage 122 which is mounted on cranks 123, 123. On each crank is a bushing 124 and a cap plate 125 is secured to the crank by means of threaded screws 126. These cap plates overlap the bushings and the parts of the carriage adjacent thereto. The cranks 123 are carried by shafts 127 respectively. At the inner end of the shaft is a bevel gear 129 and these beveled gears mesh with bevel gears 130 on the main shaft 48. As the main shaft rotates, the carriage 122 will be raised and lowered and will be moved forward and back and this gives to the bumping hammer what might be called four motions, that is a downward movement in contact with the metal, a forward movement with the metal as it presses the side seam, an upward movement from contact with the metal and then a return movement to the initial position from which it will be seen that the side seam is bumped down, tightened without any slowing up or slackening movement of the can body.

The bumping hammer is mounted in a recess in the carriage 122 and is held therein by a face plate 131. Said face plate is secured in carriage by bolts 132. Set screws 133 extending through the face plate engage the bumping hammer and holds it firmly in the carriage. Directly above the bumping hammer is a backing plate 134, the upper edge of the backing plate rests against the housing of the carriage 122. The lower face 135 of the backing plate is inclined, thus making the backing plate wedge-shaped. The upper face of the bumping hammer is also inclined with a high point at the center of the bumping hammer so that the only pressure contact between the backing up plate 134 and the bumping hammer is centrally of the hammer and this insures that the bumping hammer will press the seam with even pressure throughout. The wedge-shaped back up plate may be adjusted endwise by two adjusting screws 136 which are also provided with lock nuts 137. By moving this wedge-shaped backing up plate to the right as viewed in Fig. 20, the bumping hammer will be lowered. Of course, the set screws 133 will be first loosened in order to permit the ready adjustment by the wedge-shaped backing up plate when the backing up plate 134 is moved to the left, then the

bumping hammer may be raised. As above noted, the rectifying finger is mounted on the bumping hammer and moves therewith.

After the seam has been bumped down as shown in Fig. 63, then the side seam is finished and the operations of the body forming machine are through. The trucks continue to move the can body along the horn until they are carried underneath a conveyor chain 138 which is provided with conveying lugs 139. These conveying lugs then take up the conveying of the can bodies and carry same along to the soldering machine. The trucks following around the sprocket wheels will move out of engagement with the can bodies.

Operation.

It is thought that the operation of the machine will be perfectly clear from the detailed description given above. In summing up it may however, be said that the can bodies are formed from blanks which are rolled into a cylindrical shape after which they start on an endwise travel which is continuous. The body machines for making interlock seams so far as I am aware, prior to my invention, depend upon an intermittent action, that is, the can body is moved step by step from one station to the next station. It will readily be seen that in a heavy machine where there are heavy moving parts that this starting and stopping of the trucks and other moving parts is very detrimental and results in hard wear on the machine. By my improved machine wherein the trucks move continuously and all operations on can bodies are performed without stopping the can body or even slowing up its speed of travel, these disadvantages are all done away with. While I have described more or less in detail a preferred form of mechanism and arrangement of devices, for accomplishing this result, it will be understood that from this certain aspect the invention is directed to a body making machine wherein all the side seaming operations are performed while the can body is moving. After the blank length is formed in the cylindrical shape it is first presented by traveling trucks to the edger where the edges are bent into hook shape. It is then presented to the locator which locates these edges one above the other and interlocks the seam. It is then presented to the rectifying finger which evens up the ends of the can body preliminary to the bumping down of the seam and it is then presented to the bumping mechanism which bumps down and finishes the side seam.

It will be obvious that minor changes in the details of construction and the arrangement of the parts may be made without departing from the spirit of the invention as set forth in the appended claims.

Having thus described the invention, what I claim as new and desire to secure by Letters-Patent, is:—

1. A can body maker comprising a reciprocating supporting horn, means for moving the can bodies continuously through the machine, and means for simultaneously bending the entire side edges of the can body preparatory to interlocking the same while the can body is moving through the machine. 70
2. A can body maker comprising a reciprocating supporting horn, means for moving the can bodies continuously through the machine, means for simultaneously bending the entire side edges of the can body preparatory to interlocking the same while the can body is moving through the machine, means for interlocking the bent side edges of the can body while the can body is moving through the machine, and means for bumping together the interlocked side edges of the can body while it is moving through the machine. 75
3. A can body maker comprising a reciprocating supporting horn, means for moving the can bodies continuously through the machine, means for simultaneously bending the entire side edges of the can body preparatory to interlocking the same while the can body is moving through the machine, means for moving the horn with the can body during the bending of the side edges thereof. 80
4. A can body maker comprising a reciprocating supporting horn, means for moving the can bodies continuously through the machine, means for simultaneously bending the entire side edges of the can body preparatory to interlocking the same while the can body is moving through the machine, means for moving the horn with the can body during the bending of the side edges thereof, means for interlocking the side edges of the can body while it is moving through the machine, and means for bumping together the interlocked side edges of the can body while it is moving through the machine. 85
5. A can body maker comprising a reciprocating supporting horn, means for moving the can bodies continuously through the machine, means for simultaneously bending the entire side edges of the can body preparatory to interlocking the same while the can body is moving through the machine, means for interlocking the bent side edges of the can body while the can body is moving through the machine. 90
6. A can body maker comprising a reciprocating supporting horn, means for moving the can bodies continuously through the machine, means for simultaneously bending the entire side edges of the can body preparatory to interlocking the same while the can body is moving through the machine, means for moving the horn with the can body during the bending of the side edges thereof, and means for interlocking the side edges of the can body while it is moving through the machine. 95
7. A can body maker comprising a reciprocating supporting horn, means for moving the can bodies continuously through the machine, means for simultaneously bending the entire side edges of the can body preparatory to interlocking the same while the can body is moving through the machine, means for interlocking the bent side edges of the can body while the can body is moving through the machine, and means for bumping together the interlocked side edges of the can body while it is moving through the machine. 100
8. A can body maker comprising a reciprocating supporting horn, continuously moving means for conveying the can bodies along said horn, means for reciprocating said horn endwise, traveling trucks for conveying the can bodies along the horn, an edger for bending the side edges of the can body, means for moving said edger toward and from the horn 105 and for reciprocating the edger with the horn, and a female die member carried by the horn and cooperating with said edger. 105
9. A can body maker comprising a supporting horn, continuously moving means for conveying the can bodies along said horn, means for reciprocating said horn endwise, traveling trucks for conveying the can bodies along the horn, an edger for bending the side edges of the can body, means for moving said edger toward and from the horn 110 and for reciprocating the edger with the horn, a female die member carried by the horn and cooperating with said edger, and means for interlocking the bent edges 115 of the can body as it is traveling through the machine. 120
10. A can body maker comprising a supporting horn, continuously moving means for conveying the can bodies along said horn, means for reciprocating said horn endwise, traveling trucks for conveying the can bodies along the horn, an edger for bending the side edges of the can body, means for moving said edger toward and from the horn 125 and for reciprocating the edger with the horn, a female die member carried by the horn and cooperating with said edger, and means for interlocking the bent edges 130 of the can body as it is traveling through the machine. 130
11. A can body maker comprising a supporting horn, continuously moving means for conveying the can bodies along said horn, means for reciprocating said horn endwise, traveling trucks for conveying the can bodies along the horn, an edger for bending the side edges of the can body, means for moving said edger toward and from the 135

horn and for reciprocating the edger with the horn, a female die member carried by the horn and cooperating with said edger, means for interlocking the bent edges of the can body as it is traveling through the machine, and means for bumping together the interlocked side edges while the can body is moving through the machine.

12. A can body maker comprising a supporting horn, continuously moving means for conveying the can bodies along said horn, means for reciprocating said horn endwise, traveling trucks for conveying the can bodies along the horn, an edger for bending the side edges of the can body, means for moving said edger toward and from the horn and for reciprocating the edger with the horn, a female die member carried by the horn and cooperating with said edger, means for interlocking the bent edges of the can body as it is traveling through the machine, a rectifying finger for evening the ends of the can body after they are interlocked, and a bumping mechanism for bumping together the interlocked side edges as the can body is moving through the machine.

13. A can body maker comprising a supporting horn, continuously moving means for conveying the can bodies along said horn, means for reciprocating the horn endwise, traveling trucks for moving the can bodies along the horn, an edger, means for moving the edger toward and from the horn, and means for reciprocating the edger with the horn, said edger being timed to move with the horn and at substantially the same speed thereof while in engagement with the can body for bending the side edges thereof, and a female die bar carried by the horn and cooperating with the edger.

14. A can body maker comprising a supporting horn, continuously moving means for conveying the can bodies along said horn, means for reciprocating the horn endwise, traveling trucks for moving the can bodies along the horn, an edger, means for moving the edger toward and from the horn, means for reciprocating the edger with the horn, said edger being timed to move with the horn and at substantially the same speed thereof while in engagement with the can body for bending the side edges thereof, a female die bar carried by the horn and cooperating with the edger, a locator bar adapted to receive the bent edges and interlock the same, and guide members cooperating with the locator in interlocking the side edges.

15. A can body maker comprising a supporting horn, continuously moving means for conveying the can bodies along said horn, means for reciprocating the horn endwise, traveling trucks for moving the can bodies along the horn, an edger, means for moving the edger toward and from the

horn, means for reciprocating the edger with the horn, said edger being timed to move with the horn and at substantially the same speed thereof while in engagement with the can body for bending the side edges thereof, a female die bar carried by the horn and cooperating with the edger, a locator bar adapted to receive the bent edges and interlock the same, guide members cooperating with the locator in interlocking the side edges, and a bumper for bumping the interlocked side edges together.

16. A can body maker comprising a supporting horn, continuously moving means for conveying the can bodies along said horn, means for reciprocating the horn endwise, traveling trucks for moving the can bodies along the horn, an edger, means for moving the edger toward and from the horn, means for reciprocating the edger with the horn, said edger being timed to move with the horn and at substantially the same speed thereof while in engagement with the can body for bending the side edges thereof, a female die bar carried by the horn and cooperating with the edger, a locator bar adapted to receive the bent edges and interlock the same, guide members cooperating with the locator in interlocking the side edges, a rectifying finger for evening the ends of the can body while it is moving through the machine, and a bumper for bumping together the interlocked side edges.

17. A can body maker comprising a supporting horn, continuously moving means for conveying the can bodies along said horn, means for reciprocating said horn endwise, forming rolls for forming a cylindrical can body about the horn, a guide bar carried by the horn for receiving and guiding the side edges of the can body, an edger, means for moving the edger with the horn while in engagement with the can body, a female die bar carried by the horn and cooperating with the edger, a bumper, means for moving the bumper with the horn while said bumper is in engagement with the can body, and an anvil carried by the horn and cooperating with said bumper.

18. A can body maker comprising a supporting horn, continuously moving means for conveying the can bodies along said horn, means for reciprocating said horn endwise, forming rolls for forming a cylindrical can body about the horn, a guide bar carried by the horn for receiving and guiding the side edges of the can body, an edger, means for moving the edger with the horn while in engagement with the can body, a female die bar carried by the horn and cooperating with the edger, a bumper, means for moving the bumper with the horn while said bumper is in engagement with the can body, an anvil carried by the horn and co-

operating with said bumper, and a rectifying finger located between the edger and the bumper for evening the ends of the can body after they have been interlocked preparatory for the bumping operation.

19. A can body maker comprising a supporting horn, continuously moving means for conveying the can bodies along said horn, means for moving the supporting horn 10 endwise, trucks for conveying the can bodies along the horn, forming rolls for forming a cylindrical can body around the horn, a guide bar carried by the horn and having recesses for guiding the side edges of the can body, a female die bar carried by the horn and adapted to receive the edges from the guide bar, an edger adapted to cooperate with said female die bar in bending the side edges of the can body, a clamping member 15 adapted to engage the side portion of the can body for holding the edge thereof relative to the female die bar prior to the engagement of the edge by the edger, and means for moving the edger with the horn 20 while the edger is in engagement with the can body.

20. A can body maker comprising a supporting horn, continuously moving means for conveying the can bodies along said 25 horn, means for moving the supporting horn endwise, trucks for conveying the can bodies along the horn, forming rolls for forming a cylindrical can body around the horn, a guide bar carried by the horn and having recesses for guiding the side edges of the can body, a female die bar carried by the horn and adapted to receive the edges from the guide bar, an edger adapted to cooperate with said female die bar in bending the 30 side edges of the can body, a clamping member adapted to engage the side portion of the can body for holding the edge thereof relative to the female die bar prior to the engagement of the edge by the edger, means for moving the edger with the horn 35 while the edger is in engagement with the can body, and a locator bar carried by the machine and guides cooperating therewith for causing the bent edges of the can body to be interlocked.

21. A can body maker comprising a supporting horn, continuously moving means for conveying the can bodies along said 40 horn, means for moving the supporting horn endwise, trucks for conveying the can bodies along the horn, forming rolls for forming a cylindrical can body around the horn, a guide bar carried by the horn and having recesses for guiding the side edges of the can body, a female die bar carried by the horn and adapted to receive the edges from the guide bar, an edger adapted to cooperate with said female die bar in bending the side edges of the can body, a clamping member 45 adapted to engage the side portion of the

can body for holding the edge thereof relative to the female die bar prior to the engagement of the edge by the edger, means for moving the edger with the horn while the edger is in engagement with the can 50 body, a locator bar carried by the machine, guides cooperating therewith for causing the bent edges of the can body to be interlocked, and a rectifying finger for engaging the ends of the can body for evening the same.

22. A can body maker comprising a supporting horn, continuously moving means for conveying the can bodies along said horn, means for moving the supporting horn 55 endwise, trucks for conveying the can bodies along the horn, forming rolls for forming a cylindrical can body around the horn, a guide bar carried by the horn and having recesses for guiding the side edges of the can body, a female die bar carried by the horn and adapted to receive the edges from the guide bar, an edger adapted to cooperate with said female die bar in bending the side edges of the can body, a clamping member adapted to engage a 60 side portion of the can body for holding the edge thereof relative to the female die bar prior to the engagement of the edge by the edger, means for moving the edger with the horn while the edger is in engagement with the can body, a locator bar carried by the machine, guides cooperating therewith for causing the bent edges of the can body to be interlocked, a rectifying finger for engaging the ends of the can body for evening 65 the same, an anvil carried by the horn, a bumper cooperating with the anvil for bumping down the interlocked side edges, and means for moving said bumper with the horn while in contact with the can body.

23. A can body maker comprising a supporting horn, continuously moving means for conveying the can bodies along said horn, an edger for bending or folding the side edges of the can body, a female die bar carried by the horn and cooperating with said edger, a carriage on which said edger is mounted, means for reciprocating said carriage back and forth, means for reciprocating the horn in timing with said carriage, and means for moving the edger up and down on said carriage.

24. A can body maker comprising a supporting horn, continuously moving means for conveying the can bodies along said horn, an edger for bending or folding the side edges of the can body, a female die bar carried by the horn and cooperating with said edger, a carriage on which said edger is mounted, means for connecting the carriage with the horn whereby the horn is reciprocated back and forth with said carriage, and means for moving said edger up and down on said carriage.

25. A can body maker comprising a sup- 130

- porting horn, continuously moving means for conveying the can bodies along said horn, a female die member carried by the horn, an edger associated with said female die member, a carriage, means for supporting the carriage parallel with the horn, means for reciprocating the horn, a support mounted on said carriage, means for moving the support up and down on the carriage, a bracket mounted on the support, and means for connecting the edger to said bracket.
26. A can body maker comprising a supporting horn, continuously moving means for conveying the can bodies along said horn, a female die member carried by the horn, an edger associated with said female die member, a carriage, means for supporting the carriage, means for reciprocating the carriage parallel with the horn, means for reciprocating the horn, a support mounted on said carriage, means for moving the support up and down on the carriage, a bracket mounted on the support and adjustable toward and from the plane of movement of the carriage, and means for mounting said edger on said bracket.
27. A can body maker comprising a supporting horn, continuously moving means for conveying the can bodies along said horn, a female die member carried by the horn, an edger associated with said female die member, a carriage, means for supporting the carriage, means for reciprocating the carriage parallel with the horn, means for reciprocating the horn, a support mounted on said carriage, means for moving the support up and down on the carriage, a bracket mounted on the support and adjustable toward and from the plane of movement of the carriage, and adjustable means for connecting the edger to the bracket whereby the edger may be shifted in a direction parallel with the plane of movement of the carriage.
28. A can body maker comprising a supporting horn, continuously moving means for conveying the can bodies along said horn, means for reciprocating the horn, a female die bar carried by the horn, an edger cooperating with said die bar, a supporting bracket, a carriage mounted on said bracket, a support mounted on the carriage on which the edger is mounted, spaced shafts, cranks carried thereby, bearings mounted on the cranks, and vertical ways in the carriage in which said bearings slide whereby the rotation of the shaft moves the carriage endwise parallel with the horn.
29. A can body maker comprising a supporting horn, continuously moving means for conveying the can bodies along said horn, means for reciprocating the horn, a female die bar carried by the horn, an edger cooperating with said die bar, a carriage mounted on said bracket, a support mounted on the carriage on which the edger is mounted, spaced shafts, cranks carried thereby, bearings mounted on the cranks, and vertical ways in the carriage in which said bearings slide whereby the rotation of the shaft moves the carriage endwise parallel with the horn.
30. A can body maker comprising a supporting horn, continuously moving means for conveying the can bodies along said horn, means for reciprocating the horn, a female die bar carried by the horn, an edger cooperating with said die bar, a carriage, means for moving the carriage parallel with the movement of the horn, a support mounted on the carriage, springs for raising the support, means for depressing the support, a clamping member carried by the support and adapted to engage the can body for holding one side edge portion in the die bar, and means for mounting the edger on said support.
31. A can body maker comprising a supporting horn, continuously moving means for conveying the can bodies along said horn, means for reciprocating the horn, a female die bar carried by the horn, an edger cooperating with said die bar, a carriage, means for moving the carriage parallel with the movement of the horn, a support mounted on the carriage, springs for raising the support, means for depressing the support, a clamping member carried by the support and adapted to engage the can body for holding one side edge portion in the die bar, and means for mounting the edger on said support.
32. A can body maker comprising a supporting horn, continuously moving means for conveying the can bodies along said horn, an edger, a die member carried by the horn and co-operating with the edger, a carriage, a support mounted on the carriage to which said edger is connected, parallel shafts, means carried thereby for moving the carriage back and forth and for moving the support up and down on the carriage, a cross head connected to said support, and a link connecting the cross head with the carriage, whereby the reciprocations of the carriage are imparted to the horn.
33. A can body maker comprising a sup-

- porting horn, continuously moving means for conveying the can bodies along said horn, an edger, a die member carried by the horn and cooperating with the edger, a carriage, a support mounted on the carriage to which said edger is connected, parallel shafts, means carried thereby for moving the carriage back and forth and for moving the support up and down on the carriage, forming rolls for forming a blank into a cylindrical can body, a sleeve in front and in rear of the forming rolls, rods adapted to slide in said sleeves, a cross head at one end of the forming rolls to which said horn is connected, a cross head at the other end of the forming rolls, and a link connecting said last-named cross head with the carriage whereby the reciprocations of the carriage are imparted to the horn.
34. A can body maker comprising a supporting horn, means for reciprocating said horn, means for forming the can body around the horn and bending and interlocking the side edges of the can body, and a bumping mechanism for bumping down the side edges of the can body including an anvil carried by the horn, a bumper, means for supporting said bumper, means for moving the bumper toward and from the anvil, and means for moving the bumper with the horn while in engagement with the can body.
35. A can body maker comprising a supporting horn, means for reciprocating said horn, means for forming the can body around the horn and bending and interlocking the side edges of the can body, and a bumping mechanism for bumping down the side edges of the can body including an anvil carried by the horn, a bumper, means for supporting said bumper, means for moving the bumper toward and from the anvil, and a rectifying finger carried by the bumper mechanism for evening the ends of the can body prior to the bumping of the same.
36. A can body maker comprising a supporting horn, means for reciprocating said horn, means for forming the can body around the horn and bending and interlocking the side edges of the can body, and a bumping mechanism including an anvil mounted in the horn, a bumper, means for moving said bumper into and out of contact with the can body on the horn, means for moving the bumper with the can body while in contact therewith, and means whereby said bumper may be adjusted on its operating mechanism to vary the bumping pressure of the same on the can body.
37. A can body maker comprising a supporting horn, means for reciprocating said horn, means for forming the can body around the horn and bending and interlocking the side edges of the can body, and a bumping mechanism including an anvil mounted in the horn, a bumper, means for moving said bumper into and out of contact with the can body on the horn, means for moving the bumper with the can body while in contact therewith, and means whereby said bumper may be adjusted on its operating mechanism to vary the bumping pressure of the same on the can body.
38. A can body maker comprising a supporting horn, means for reciprocating said horn, means for forming the can body around the horn and bending and interlocking the side edges of the can body, and a bumping mechanism including parallel shafts each having a crank, a support carried by the cranks and movable bodily therewith, said shafts being disposed so that the support moves toward and from the horn and back and forth lengthwise of the horn, and a bumper carried by said support.
39. A can body maker comprising a supporting horn, means for reciprocating said horn, means for forming the can body around the horn and bending and interlocking the side edges of the can body, and a bumping mechanism including parallel shafts each having a crank, a support carried by the cranks and movable bodily therewith, said shafts being disposed so that the support moves toward and from the horn and back and forth lengthwise of the horn, a bumper having an inclined upper edge mounted in said support, and a wedge engaging said inclined upper edge for adjusting the bumper on the support.
40. A can body maker comprising a supporting horn, means for reciprocating said horn, means for forming the can body around the horn and bending and interlocking the side edges of the can body, and a bumping mechanism including parallel shafts each having a crank, a support carried by the cranks and movable bodily therewith, said shafts being disposed so that the support moves toward and from the horn and back and forth lengthwise of the horn, a bumper having an inclined upper edge mounted in said support, a wedge engaging said inclined upper edge for adjusting the bumper on the support, and means for shifting the wedge and holding the wedge in adjusted position.
41. A can body maker comprising a supporting horn, means for reciprocating said horn, means for forming the can body around the horn and bending and interlocking the side edges of the can body, and a bumping mechanism including parallel shafts, cranks carried by the shafts, a support mounted on the cranks and movable

toward and from the horn and endwise of the horn, a bumper carried by the support, a rectifying finger pivoted on said support, said horn having a can shoulder adapted to be engaged by the rectifying finger whereby the rectifying finger is swung to even up the ends of the can body prior to the bumper engaging the can body.

42. A can body maker comprising a supporting horn, means for reciprocating said horn, means for forming the can body around the horn and bending and interlocking the side edges of the can body, and a bumping mechanism including parallel shafts, cranks carried by the shafts, a sup-

port mounted on the cranks and movable toward and from the horn and endwise of the horn, a bumper carried by the support, a rectifying finger pivoted on said support, said horn having a cam shoulder adapted to be engaged by the rectifying finger whereby the rectifying finger is swung to even up the ends of the can body prior to the bumper engaging the can body, and means whereby the bumper may be adjusted on the support to vary the bumping pressure on the can body.

In testimony whereof, I affix my signature.

ALFRED L. KRONQUEST.
